UNITED STATES PATENT OFFICE.

HENRY LUND SMITH, OF PATERSON, NEW JERSEY.

HEAD-SUPPORTING BATHING APPLIANCE.

Application filed February 27, 1922. Serial No. 539,656.

To all whom it may concern:

Be it known that I, HENRY LUND SMITH, a citizen of the United States, residing at Paterson, in the county of Passaic and State 5 of New Jersey, have invented certain new and useful Improvements in Head-Supporting Bathing Appliances, of which the following is a specification.

This invention relates to bathing appliances and the like and particularly to buoyant means for use in supporting the head in swimming or learning to swim. The objects 10 are to provide means which will support the wearer's head while in the water, as by affording a rest for his chin when swimming back up or for the back of the head when swimming back down or "floating," without exerting any direct buoyant effect on any other parts of his body, which are to be left 15 quite as free as if any means for assisting in swimming were not present; and to construct this means so that it will not be an annoyance to the wearer when out of the water, but will hang down on his chest or at 20 his back, leaving his head quite free at that time, and yet when he is in the water and it is active in supporting his head it will be effectually retained in some definite position and against working around the wearer's neck. 25

Fig. 1 shows one form of the invention in plan;

Fig. 2 is a view showing said form in plan and as it would be when attached to the wearer;

Fig. 3 is a side elevation of the form shown in Fig. 1;

Fig. 4 is an isometric view of another form of the invention; and

Fig. 5 is a side elevation of the form shown in Fig. 4.

Referring to Figs. 1, 2 and 3; *a* designates a buoyant member which may be made buoyant in any way, as by being a hollow flexible bulb which may be inflated, *a'* indicating 45 an inflating tube (omitted in Figs. 3 and 5). In the best form of my invention this member is quite like a flat cushion, what I term the body portion thereof, or the portion at the near side of the line *x*—*x* in Fig. 1 or Fig. 50 2, having greater dimension in every horizontal direction than any vertical dimension thereof; in the form now being described at what I treat as the rear of the member (i. e., projecting rearwardly from said body

portion) it has two projecting horns *b* *b* 55 which are curved inwardly toward each other, the curvature being preferably such, in fact, as nearly to correspond to the cross section of the human neck from the tip of one horn to the tip of the other, as shown in Fig. 2, excepting that when the device is applied to the neck the extremities of the horns stand inwardly deflected so that they will exert slight pressure against the neck at *c* *c*. *d* designates tapes which are attached to the horns and may be tied together to secure the body *a* in a position on the wearer's neck.

The object in giving the member *a* the flattened form is to make it have little vertical dimension or thickness and yet considerable 70 buoyancy, so that it not only will not oppose undue resistance to the water but when attached to the wearer it may have free movement up and down pivotally, as between his chest and his chin, for example, bearing 75 up against his chin and thus supporting his head when in the water and resting against his chest when out of the water. I find that buoyant bodies which are formed to fit the recess between the chin and the chest of the 80 wearer when out of the water are a source of great discomfort at that time, besides being so bulky that when in use in the water they become an obstacle to rather than an aid in swimming. In order to keep the device 85 in the form now being described from working around the neck of the wearer a certain amount of friction is obtained by the horns *b* on the wearer's neck at the points *c*; on these points, moreover, the member *a* can 90 move up and down pivotally as indicated by the solid and dotted lines in Fig. 3.

Referring to Figs. 4 and 5 the buoyant member *a'* is substantially the same as the body *a* already described excepting that the horns *b'* do not extend so far rearwardly as the horns *b* and have no provision for gripping the wearer's neck as at the point *c*. The appliance in this form includes a harness adapted to girdle the wearer's body, the same including a skeleton breast-piece *e* having a belt portion *f* consisting of two tapes to be tied around the wearer's waist and two other tapes *g* to be passed over the wearer's shoulders and tied together. On the upper 100 part of the breast-piece *e* the member *a'* is pivoted to move up and down, as by means of the fabric hinges *h*.

Having thus fully described my invention, what I claim and desire to secure by Letters Patent is:

A head-supporting bathing appliance comprising a buoyant member including a body portion having when resting on the water its dimension in every horizontal direction greater than the vertical dimension thereof, said member also including tapering horns 15 forming horizontal extensions of said body portion and adapted to fit around the wear-

er's neck, and means, connected to the tips of the horns, for securing the appliance to the wearer with his neck received between the horns, said means having flexible portions adjacent to the horns and permitting said member to freely shift up and down on said portions and said member constituting all of the appliance that is buoyant.

In testimony whereof I affix my signature.

HENRY LUND SMITH.
